(57) **CLAIM**

The ornamental design for a pour over coffee maker, as shown and described.

DESCRIPTION

FIG. 1 is a front elevational view of a pour over coffee maker showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a top, front and left side perspective view thereof;

FIG. 8 is a top, rear and left side perspective view thereof;

FIG. 9 is a top, rear and right side perspective view thereof;

FIG. 10 is a top, front and right side perspective view thereof;

FIG. 11 is a bottom, front and right side perspective view thereof;

FIG. 12 is a bottom, front and left side perspective view thereof; and,

FIG. 13 is an exploded top, front and left side perspective view thereof.

The de-emphasized and half-tone portion shown within the broken lines in FIG. 13 depicts a portion of the pour over coffee maker that forms no part of the claimed design.

1 Claim, 13 Drawing Sheets
